UNITED STATES PATENT OFFICE.

GEORGE H. WINTERBOTTOM, OF MANCHESTER, ENGLAND, ASSIGNOR TO
ARCHIBALD WINTERBOTTOM & SONS, OF SAME PLACE.

DESIGN FOR BOOKBINDERS' CLOTH.

SPECIFICATION forming part of Design No. 22,183, dated January 31, 1893.

Application filed June 12, 1890. Serial No. 355,250. Term of patent 14 years.

To all whom it may concern:

Be it known that I, GEORGE HAROLD WINTERBOTTOM, a subject of the Queen of Great Britain, residing at Manchester, England, 5 have invented a new and original Design for Bookbinders' Cloth, of which the following is a specification.

This invention relates to a design for bookbinders' cloth on which a grain is formed by irregular depressions and raised portions or panels between said depressions, to which irregular surface grain is imparted.

The nature of my design is fully shown in the accompanying photograph, to which reference is made.

The design on the surface of the cloth is formed of irregular depressions *a*, between which raised portions or panels *b* of irregular shape are formed. The surface of the raised

portions is broken up, so as to form an irregular grain therein. The irregular depressions or veins intersect in an irregular manner with each other and form with the raised broken up portions a pattern in the nature of an irregularly-etched metal plate in which lines or 25 veins of greater depth are formed.

Having thus described my design, I claim as new and desire to secure by Letters Patent:—

The design for bookbinders' cloth, substantially as shown and described. 30

In testimony that I claim the foregoing as my invention I have signed my name in presence of two subscribing witnesses.

G. H. WINTERBOTTOM.

Witnesses:

ARTHUR C. HALL,

HY. BLAIR,

9 Mount St., Manchester.
